ELECTRON TUBE MOUNT OF THE SHIELDED ELEMENT TYPE

George L. Rishell, Emporium, Pa., assignor to
Hygrade Sylvania Corporation, Emporium, Pa.,
a corporation of Massachusetts

Application April 10, 1941, Serial No. 387,839

13 Claims. (Cl. 250—27.5)

This invention refers to electron discharge devices and in particular to discharge tubes in which several sections are mounted in a single evacuated envelope.

The simplest example of a multisectioinal discharge tube of this type is a combination of a diode section with a triode section, one section being mounted above the other, and having a common thermionic cathode extending through the length of both sections. Usually the diode section is at the lower end of the tube; that is, at the end nearest to the stem or header, through which the lead-in conductors are sealed. Tubes of this kind are quite commonly used as detector-amplifiers. The triode section serves as amplifier for the high frequency signals demodulated by the diode section. The amplifier section may be a pentode as well as a triode, and frequently, two diodes are mounted in the diode section, one of which may be used for AVC, the other for demodulation.

In order to insure electrical independence of the two sections of the tube from each other, a box or barrel-shaped metal shield is usually applied, which prevents undesirable electric stray fields of one section from penetrating into the discharge space of the other. A shield of this kind is preferably so designed, that it reduces the exposure of the leads coming from the electrodes of one section to those of the other section to a minimum.

The application of electrostatic shields between sections of multisectioinal tubes is, of course, not restricted to the case of diode-triodes, but is quite essential in many other multiple section tubes, as in triode-hexodes or triode-heptodes, in short in all multiple-section tubes in which a complete electrostatic shielding of one section from the other is desirable.

In all these cases, the designer is faced with a number of problems, which partly originate from the difficulty of welding the increased number of metallic connections within the small space available for the purpose, partly from the difficulty of insuring a uniform spacing between the different sections, so as to obtain a construction which will give a uniform product with respect to electrical characteristics and geometrical dimensions in line with the requirements of modern mass production methods.

The present invention solves some of these problems for multisectioinal tubes substantially by so designing one of the elements of one section of a multisectioinal tube that it serves simultaneously the purposes of shielding one section

from the other, spacing two sections from each other, and partly for mechanically locking together the parts of a unitary mount which forms another section of the tube.

5 The invention also takes care of a free passing of the exhaust gases developed in breaking down the cathode coating. It has been noted in many cases, that the breakdown of the cathode coating of a well shielded tube section is delayed because the gases developed in this section meet too much resistance in their flow toward the exhaust tubulation and finally into the exhaust system. By the particular shape of the spacing members, which are rigidly attached to the shielding member, a free flow of these gases out of the shielded section is insured according to the invention, without sacrificing any of the good shielding properties required for the electrical independence of the different tube sections.

20 Accordingly, it is a principal object of the invention to devise a multisectioinal tube in which one tube element performs different functions for which the prior art has employed several elements.

25 A feature of the invention refers to an electrostatic shield, which is so designed that it automatically spaces two sections of a multisectioinal tube accurately from each other.

Another feature of the invention refers to the 30 partial support given to the unity of the mount of one of the sections, which prior to the invention had to be secured by separate means.

Another principal object of the invention refers to the simplification of the mounting operation of multisectioinal tubes.

35 One feature of the invention refers to the automatic and accurate spacing of two sections of a tube, which avoids the necessity of using special gauges for securing uniform spacing between sections.

40 Another feature of the invention is the reduction of the number of welding operations heretofore considered necessary during the mounting of the tube.

45 Another important feature of the invention refers to the comparative freedom of the exhaust path for the gases developed in the diode section.

Finally, it is the object of the invention to 50 design an electrostatic shield for use between two sections of a multisectioinal tube, which can easily be formed from a single piece of sheet metal.

The invention is described in detail in connection with the drawings, in which

Fig. 1 is a longitudinal section of a mount constructed according to one embodiment of the invention.

Fig. 2 is a longitudinal section of a mount incorporating another embodiment of the invention.

Fig. 3 shows an isometric view of the new electrostatic shield.

Figs. 4 and 5 show top and side views of the new tube element.

Fig. 6 shows a view of another embodiment of the invention.

Fig. 7 shows a side view of a complete tube incorporating the invention.

Fig. 8 is an enlarged detail view of part of Fig. 1.

Fig. 9 shows a modification of the diode shield of Figs. 1-8.

For the sake of simplicity, the drawings show embodiments of the invention as applied to a double-diode triode. Evidently the simplification in mounting and the elimination of separate supports, eyelets, straps, mounting jigs and gauges, as well as the improved appearance of the mount, all of which are characteristic of the invention are independent of the specific structure of the sections forming the tube; and may also be obtained, by the means disclosed herein, for tubes containing more than two sections. It will, therefore, not be necessary to enumerate the different combinations of two and more sections within a single envelope to which the principles of the invention can be equally well applied.

Referring now to Figure 1, numeral 1 represents a glass header or stem with eight rigid lead prongs sealed through it in a vacuum tight manner. To two of the leads, 2 and 3, are welded the rigid mount supports 30, 31, which carry the diode mica spacer 29 at the bottom on rectangular bends 32 and 33, which are in a plane parallel to the disc-shaped part of header 1. The bottom diode spacer is provided with holes through which the upright parts 40 and 41 of the mount supports are threaded. This diode spacer also has holes through which the diode supports extend, and a hole in the center for taking up the cathode 5. A box-like diode shield 17 is welded to the mount supports 30 and 31. Diode shield 17, and the diode plates (not shown), bottom spacer 29 and the lower part of cathode 5 form together the bottom or diode-section of the tube. An opening 27 is provided in the center of the top section of diode shield 17 (see Figure 3) to permit the cathode to pass through the top wall of the diode shield. The diode shield 17 is provided with ears or tabs 24, 25, by which the bottom mount spacer 13 of the top section 9 of the tube is supported. Bottom spacer 13 of triode section (top section) 9 is preferably of a construction disclosed in Patent No. 2,250,409. As explained in said application, the use of this mount spacer allows a rigid centering of the cathode without any danger of scratching off any cathode coating from the lower section of the cathode during the operation of mounting the cathode into the spacer. A detailed description of the steps of mounting the cathode and of slipping the spacer 13 over the mount supports 30, 31 is given in the above quoted Patent No. 2,250,409. Holes and slots in spacer 13 are provided to take up the tabs 14 of plate 10 and the side rod support of grid 11. Top spacer 12 is provided with similar slots and holes too for spacing grid, plate and cathode at the top. (A

getter support and container 43 may be welded to one of supports 30 or 31.)

Connectors are provided from the different electrodes to the respective lead-in conductors of header 1 in known manner. One or both of the plate tabs 14 may be bent at the bottom of mount spacer 13, but it is not necessary to bend over any of the plate tabs 14 on the top spacer 12 in order to insure a rigid unitary mount of top section 9. It is sufficient to weld the cathode tab 42 to one of the mount supports 30 or 31 in order to prevent top spacer 12 from slipping upward on the supports 30 and 41. This connection from cathode to one of the mount supports is desirable also for the purpose of making the ground or cathode connection to the diode shield.

It will be noticed, that the top section forms a unitary mount between the two mount spacers 12 and 13, and that not a single eyelet, strap or other element is used which elements ordinarily fulfill no other duty than merely to insure a longitudinal spacing of the different top section elements, or an interlocking of this section in itself. The bottom spacer rests firmly on the diode shield ears 24 and 25. These ears form an integral part of the diode shield, and serve in addition for the correct longitudinal spacing of the diode shield top surface from the mount spacer 13. The cathode tab, welded to the top end of one of the supports 30 or 31 near to and above mount spacer 12 prevents the longitudinal motion of this top spacer. The main function, of this welded connection is, however, the formation of the metallic contact between cathode and the diode shield. In this way it comes about that a complete rigid top section is formed by grid 11, plate 10 and mount spacers 12 and 13 without the usual applications of straps or eyelets welded to at least one of the supports for the only purpose of securing a rigid longitudinal spacing of the parts forming that section of the tube.

The invention is not limited to the elimination of holding means for the mount to the extent described above. Swedging of the supports 30 and 31 (not shown in the drawings) may be used to prevent the top mica spacer 12 from slipping away from the top mount. If desired, the plate tabs 14 may be bent over on the top mount spacer 12, in order to insure longitudinal spacing of the top section 9 in itself.

Fig. 2 shows another embodiment of the invention. Here, again the bottom mount spacer 13 rests on the ears 24 and 25 of shield 17, but separate support wires 20 and 21 are used for supporting the diode plates (not shown) and separate supports 22 and 23 are provided for shield 17, while the plate supports 18, 19, support only the top section. The connections between the electrodes of the tube and the lead-in conductors may be made in any known way. The idea of the invention, in this embodiment, being the use of ears 24 and 25, rigidly connected to the shield 17 for supporting the top section 9, and spacing its lower end from the top-surface of shield 17.

While shield 17 may be made in any manner convenient in a given production set-up, the preferred method of making the shield from a single piece is indicated in Fig. 6. Numeral 44 is the top part of the shield, with the opening 27 for the cathode. In symmetrical array, side walls 49 and 50, with flaps 45, 46 and 47 and 48 and ears 24 and 25, are cut out. Channels 28 (see Figure

3) are formed from flaps 45, 46, 47 and 48 in successive operations, as well as a number of strengthening ribs 52.

If desired, channels 23 may be closed at any points along their lengths by pinching (see Figures 2 and 5, points marked "A"), or by allowing the ears 24 and 25 to extend horizontally over the channels before bending them upward, so as to form stops for the support rods 22 and 23 as shown in Fig. 9.

The free passage of the break-down gases developed by that section of the cathode which is covered by the shielding element 17 is insured according to the invention by providing the ears 24 and 25 of the diode shield at the left and right side of the mount between spacer 13 and top surface 44 of the diode shield. This leaves the entire front and back surface between spacer 13 and top surface 44 free for the passage of these gases.

Fig. 7 finally shows an elevational view of a complete tube made substantially as described in connection with Fig. 1, the corresponding parts in Figs. 1 and 6 bearing the same designation numerals. In Fig. 7, the bulb 50 is of glass and is provided with a special plug-in shielding and supporting base 51 such as described in detail in Patent No. 2,250,184.

What I claim is:

1. In an electron tube mount, a pair of uprights, a plurality of electrode sections in superposed relation, a box-like shield for one of said sections rigidly fastened to said uprights, said shield having a plurality of integral vertically extending struck out tabs extending therefrom and in engagement with the adjacent end of the superposed section, and upon which the weight of said superposed section is carried.

2. In an electron tube mount, a pair of uprights, a plurality of electrode sections, means to support said sections in end-on relation but spaced longitudinally from each other, a box-like shield for one of said sections said shield being rigidly fastened to said uprights and carrying integral vertically extending struck out projections having their ends in abutting relation with the adjacent end of the other section to predetermine the longitudinal spacing of said sections, the weight of said other section being carried by said projections.

3. In an electron tube mount, a plurality of electrode sections, a pair of uprights for supporting said sections in superposed relation, a box-like shield substantially enclosing the lower section, said shield having a plurality of integral vertically extending struck out projections at its upper end abutting against the lower end of the other electrode section to fix the spacing between the two sections, the weight of said upper section being carried by said projections.

4. In an electron tube mount, a pair of parallel uprights, a pair of superposed electrode sections each having at its lower end a transversely extending electrode spacer member and through which said uprights pass, means to limit the downward movement of the spacer for the lower section, a box-like shield substantially enclosing said lower section, and means to limit the downward movement of the spacer member of the upper section, the last-mentioned means comprising a pair of integral tabs vertically extending from said shield and abutting the last-mentioned

spacer member, said tabs supporting the weight of said upper section.

5. An electron tube mount according to claim 4 in which said box-like shield has at opposite sides lugs through which said parallel uprights pass.

6. An electron tube mount according to claim 4 in which the said box-like shield rests at its lower end on the first-mentioned spacer member.

7. In an electron tube mount, a bottom electrode spacer, a top electrode spacer, an intermediate electrode spacer, all said spacers being parallel and extending substantially transverse to the vertical axis of the tube, a pair of parallel uprights extending through the three spacers, an electrode section located between the bottom and intermediate spacers, another electrode section located between the top and intermediate spacers, means to fix the spacings of said sections on said uprights, the last-mentioned means comprising a box-like shield substantially enclosing said lower section and having upwardly extending integral lugs abutting against said intermediate spacer and carrying the weight of said other electrode section, and means to limit the downward and upward movement of the sections and spacers on said uprights.

8. An electron tube mount according to claim 7 in which the last-mentioned means comprises an offset portion on the uprights engaging the bottom spacer, and a projection from one of said uprights engaging the top spacer.

9. An electron tube mount according to claim 7 in which the means for limiting the movement of the sections on the uprights consists substantially entirely of means engaging the bottom spacer and means engaging the top spacer.

10. A shield member for electron tubes consisting of a box-like metal portion having lateral lugs for slidably assembling the shield on a pair of uprights and a pair of integral upwardly extending struck out lugs at the top of the shield, the windows left by said struck out lugs providing substantially free vertical paths for the passage of gases developed during evacuation of the tube.

11. A shield member according to claim 10 in which said box-like metal portion has at opposite sides a pair of channels to receive support rods, and means cooperating with said channels to locate said shield member on said rods.

12. A shield member according to claim 10 in which said box-like metal portion has at opposite sides a pair of channels to receive support rods, and said lugs extend outwardly above said channels to limit the downward movement of said shield member on said support rods.

13. An electron tube mount comprising a header, a pair of parallel spaced uprights carried by said header, another pair of parallel spaced uprights carried by said header, an electrode assembly supported by and between the first-mentioned uprights, a second electrode assembly supported by and between the second pair of uprights in superposed spaced relation to the first electrode assembly, and means to fix the spacing of said assemblies comprising a box-like shield substantially enclosing the first assembly and having integral upstanding projections abutting against the second assembly and upon which the weight of said second assembly is carried.

GEORGE L. RISHELL,
